UNITED STATES PATENT OFFICE.

HARVEY L. GLIDDEN, OF NATICK, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

CUT-SOLE RACK.

1,313,289.

Specification of Letters Patent. Patented Aug. 19, 1919.

Application filed February 19, 1916. Serial No. 79,434.

To all whom it may concern:

Be it known that I, HARVEY L. GLIDDEN, a citizen of the United States, residing at Natick, in the county of Middlesex and 5 State of Massachusetts, have invented certain Improvements in Cut-Sole Racks, of which the following description, in connection with the accompanying drawings, is a specification, like reference characters on 10 the drawings indicating like parts in the several figures.

This invention relates to racks and is herein shown embodied in a cut-sole rack such as is used in shoe factories to store and 15 transport quantities of cut-soles. It is found that the problem of storage of non-used racks becomes a serious matter in shoe factories. The number of racks in use varies greatly from time to time and as the 20 racks are bulky many factories fail to have on hand the number which they need. It is obvious also that the cost of such bulky articles is increased by freight charges.

A demand has therefore arisen in the 25 trade for racks which can be readily knocked down and packed away in small compass when not in use. Shoe racks have heretofore been frequently made of wood because of the lightness of this material. 30 Many racks, however, are coming into use which are built of steel frames having wooden shelves and partitions. It has been recognized as desirable that such racks be made entirely of non-combustible material 35 in order to diminish the fire risk.

It is the object of my present invention to provide a rack in which defects of racks heretofore used shall be obviated. I have herein shown and described a rack which is 40 so constructed that it may be readily knocked down without the use of special tools and without the loss of much time; in which all the fastenings which have to be loosened in the knocking-down operation 45 are a small number of bolts; and which, while light, is built entirely of metal.

In the accompanying drawings,—

Figure 1 is a front elevation of the rack, 50 Fig. 2 is a section on the line 2—2 of Fig. 1,

Fig. 3 is a section on the line 3—3 of Fig. 2, and

Fig. 4 is a section on the line 4—4 of Fig. 3.

The main frame of the rack is built substantially as shown in the patent to Hammond, No. 1,100,072. It consists of a bottom frame 10 having casters 11, upright end frames 12, lateral braces 13 and end braces 14 substantially as in the patent referred to. 55 In each of the end frames 12 are bolted a series of angles 15 for supporting the shelves. These angles have their horizontal flanges extending inward. A series of tubes 16 slotted at each end are mounted upon the 60 horizontal flanges of opposite angle irons 15 and riveted thereto substantially as shown in the patent to Hammond, No. 1,108,363. The ends of the tubes bear 65 squarely against the vertical flanges of the angle irons 15 and the bottoms of the slots in the tubes bear squarely upon the horizontal flanges of the angle irons 15 and thus a stiff rigid construction of shelf is secured. 70 The shelf can be separated from the main frame by simply taking out the four bolts at the ends of its two angles 15. The two lower shelves shown in the drawings are 75 tipped at a slight angle with the horizontal in order to make the piles of material 80 stored upon them (the rack shown in the drawings is designed for cut-soles 17 as shown in Fig. 3) more stable and easier to handle. The rear and lateral partitions are formed of small steel rods 18. The tubes 85 of the lower shelf have holes bored through their upper walls in alignment with one another so as to form rows spaced apart a little more than the width of a cut-sole and the 90 rearmost tube has a series of holes which are more closely spaced or are offset from the rows in the other tubes in order to provide a rear wall for the pockets marked off by the rows in the other tubes (see Fig. 3). The tubes of the intermediate shelves have 95 registering holes in their top and bottom walls forming a series registering vertically with the series described in connection with the bottom shelf. The tubes in the top shelf are bored so as to present a lower series of 100 openings in register with those in the lower shelves but with the holes in the upper walls of the tubes slightly offset as shown in Fig. 4. This slight lack of registration makes it necessary to bend the steel rods 18 slightly 105 as they are forced in from the top. When they have been run through the shelves with their bottom ends resting upon the bottom

walls of the lower set of tubes, their upper ends slip through the upper holes in the upper tubes and the rods straighten out, being thus locked in position, as shown in Fig. 4. A rod can be easily removed by grasping it between the upper and the next lower shelf and bending it sidewise enough to point its upper end at the upper hole in the upper tube and then sliding it out of the rack.

The rack described is all metal and consequently fire proof. It is at the same time light and easy to handle. It can be taken apart and folded up in small compass by merely removing the small bolts at the ends of the shelves which will permit the entire interior of the rack to be removed. The rods can then be drawn out through the shelves and packed flat with them while the base frame and its end uprights can be folded up as described in Patent No. 1,100,072.

Having described my invention what I claim as new and desire to secure by United States Letters Patent is:

1. A rack comprising a plurality of spaced partition members having registering openings therein, a supplemental outer partition member having an opening therein out of alinement with said registering openings, and a flexible member inserted through said registering and non-alining openings to form a partition extending substantially perpendicularly relatively to said first-named partition members.

2. A rack comprising a series of spaced transversely extending shelf members, all but the outer member of the series having a plurality of longitudinally and vertically alined openings and said outer member having openings slightly out of register with said alined openings, and flexible members inserted through said alined and non-registering openings to form partition mem-

bers extending substantially perpendicularly to said transverse shelf members.

3. A rack comprising a series of partition members having registering openings, the outer member of said series being tubular and having two openings slightly offset relatively to each other and substantially alining with the apertures in the other partition members and a flexible partition member for insertion through the apertures in said tubular member and said other partition members whereby when said flexible member is inserted in position it is locked against withdrawal.

4. A rack comprising series of spaced transversely extending shelf members having vertically alining apertures one of said apertures being slightly offset from others of the series whereby when a flexible partition member is inserted through said apertures it will move out of alinement with said offset aperture and be held against withdrawal.

5. A rack having spaced shelf members in fixed relation, said members having a series of alining apertures, one of said apertures being slightly offset from the others of the series whereby when a flexible partition member is inserted through said apertures to extend substantially perpendicularly of said shelf members it will be held against withdrawal.

6. A rack having a series of spaced transverse shelf members with vertically alining apertures, an abutment at one end of the series, and a member at the other end of the series having an aperture slightly offset from the said alining apertures whereby a flexible partition member may be inserted endwise through said apertures and be locked in position.

In testimony whereof I have signed my name to this specification.

HARVEY L. GLIDDEN.
